UNITED STATES PATENT OFFICE.

CHARLES J. SMITH, OF SPRINGFIELD, ILLINOIS.

DESIGN FOR A BUTTON.

44,693.

Specification for Design.

Patented Sept. 23, 1913.

Application filed March 5, 1913. Serial No. 752,228. Term of patent 7 years.

To all whom it may concern:

Be it known that I, CHARLES J. SMITH, a citizen of the United States, residing at Springfield, in the county of Sangamon and State of Illinois, have invented a new, original, and ornamental Design for Buttons, of which the following is a specification, reference being had to the accompanying drawing, forming part thereof.

Figures 1, and 2, respectively are a front elevation and a rear elevation of a button embodying my design.

The face of the button has the contour of a triangle with rounded points. The lower end of the triangle extends somewhat be-

yond the circumference of the back of the button and the representation of an arrow is inclosed within the triangle, as shown. The contour of the back of the button is circular and is ornamented with a circular series of ellipses connected by circles, as shown.

I claim—

The ornamental design for a button, as shown and described.

CHARLES J. SMITH.
